(57) **CLAIM**

The ornamental design for a speaker for portable audio player, as shown and described.

DESCRIPTION

FIG. 1 is a front perspective view of a speaker for portable audio player showing our new design;

FIG. 2 is front elevational view thereof;

FIG. 3 is a side elevational view thereof;

FIG. 4 is a top perspective view thereof; and,

FIG. 5 is a bottom plan view thereof.

The broken line showing on the drawing disclosure is for illustrative purposes only and forms no part of the claimed design.
